UNITED STATES PATENT OFFICE.

FRANK TYSON, OF CANTON, OHIO, ASSIGNOR TO THE TYSON COMPANY, OF CANTON, OHIO, A CORPORATION OF OHIO.

DESIGN FOR AN ICE-CREAM-FREEZER BASE.

42,377.

Specification for Design.

Patented Mar. 26, 1912.

Application filed January 8, 1912. Serial No. 670,108. Term of patent 14 years.

To all whom it may concern:

Be it known that I, FRANK TYSON, a citizen of the United States, residing at Canton, in the county of Stark and State of Ohio, have invented a new, original, and ornamental Design for Ice-Cream-Freezer Bases, of which the following is a specification, reference being had to the accompanying drawing, forming part hereof.

The figure is a perspective view of an ice cream freezer, showing my new design.

I claim:

The ornamental design for an ice cream freezer base, as shown.

FRANK TYSON.

Witnesses:

RUTH A. MILLER,
RAY F. KOHL.
